APPARATUS FOR SEPARATION OF
METALLIC VALUES

Albert Hanak, Elkins Park, Pa.

Application October 15, 1942, Serial No. 462,120

3 Claims. (Cl. 266—18)

This invention relates to an apparatus for the separation of low melting point metals and alloys from higher melting point metals, and in particular is directed to an apparatus for the separation of such commingled metallic values.

In industrial operations at well as in salvaging obsolete articles of metals, there result mixtures of metals and alloys, which, if melted in a smelter, yield industrially useless or undesirable alloys. If however, these mixtures of soldered or babbitted or fusible metal filled articles are subjected to a preliminary treatment, the components can be then returned to new usefulness. It is quite evident that the more thorough is this preliminary treatment, the greater are the values recovered and the simpler and cheaper are any subsequent treatments necessary to return the component parts to new industrial and commercial usefulness.

The many types of equipment presently employed for the above purposes may attain a certain degree of success for a particular article for which they are designed. For instance, there are several types of so-called "radiator sweaters" which permit the separation of solder from the brass, but in furnaces of such limited utility, one cannot separate the lead core of jacketed bullets, nor the babbitt of babbitted bearings, nor anti-friction chips from brass or iron chips, etc.

The present invention on the other hand, provides an equipment in which all manner of separations can be performed and which, in efficiency, ease of operation, cost of installation, etc., supersedes all the presently employed types of equipment.

It is, accordingly, an object of the invention to separate metals like lead and lead alloys or tin and tin alloys from metals like copper or copper alloys, or from iron, steel, nickel, aluminum, and zinc and their alloys.

Another object of the invention is to separate the low melting point metals and alloys from high melting point metals and alloys when these are mixed in the form of chips, turnings, borings, or the like.

Another object of the invention is to separate low melting metals and alloys from soldered or babbitted articles, where a vigorous and continuous jolting is essential to complete such an operation.

Another object of the invention is to separate lead or lead alloys from ammunition, possible only by a continuous tumbling action.

Another object of the invention is to separate the low melting metals from the high melting

ones in a suitable and adjustable atmosphere and temperature.

The essence of the invention which renders the foregoing objects possible of accomplishment resides in the provision of means for:

- (a) Heating a mass containing mechanical mixtures or adherences of low and high melting point metallic values;
- (b) Maintaining the mass in a condition of constant tumbling;
- (c) Continuously and effectively removing the lower melting point values as they liquefy;
- (d) Maintaining conditions of suitable and adjustable atmospheres and temperatures;
- (e) Removing undesirable substances from the mass;
- (f) Recovering volatile or gaseously entrained values produced in the course of the separatory operation.

Further objects and a fuller understanding of the invention will be gathered upon reading the following detailed description in connection with the accompanying drawings, wherein:

Figure 1 is a diagrammatic illustration of the apparatus for effecting the separation of low melting point metals and alloys from higher melting point metallic materials constructed in accordance with the present invention.

Figure 2 is a view in section taken on the line 2—2 of Figure 1.

Figure 3 is a view in section taken on the line 3—3 of Figure 1.

Figure 4 is a view in section taken on the line 4—4 of Figure 1 and looking in the direction of the arrows.

Figure 5 is a view of the cylindrical shell, partially torn away, showing the internal construction thereof.

Figure 6 is an end view of the cylindrical shell of Figure 5.

With reference to the above drawings, a cylindrical steel shell of suitable thickness, illustrated at 10, is rotatably supported on hollow steel trunnions 11 which rest on roller bearings 12 mounted on stands 13. The cylindrical shell is insulated by a layer of heat insulating material 14 such as magnesia, or rock wool insulation, and the latter is held in place by a steel outer cover 15. The shell is rotated by means of a cogwheel 16 fastened to one end of the cylindrical shell and motivated by a variable speed motor 17 through gear-reducer 18 and link belt chain 20. The cylindrical shell is provided with a charging or discharging opening 21, which is closed with an

interchangeable perforated door 22, when the cylinder is in operation.

The heating is accomplished by a gas burner 23 inserted through one of the hollow trunnions 11, the secondary air being supplied through pipe 24 from a blower 25. The products of combustion are exhausted through the opposite hollow trunnion and appropriate cooling arrangement 26 by means of exhaust fan 27 and thence blown into baghouse 28 for the recovery of dust containing metal particles.

The cylindrical shell is internally provided with an arrangement of steel fins 30 welded thereto. These fins follow the curvature of the cylinder from the ends to the charging door. Their important function will be described later.

In operating the equipment, it is first preheated and then a charge of the material consisting of mixtures and/or adherences of low melting point and higher melting point metallic values is introduced through the opening 21, and the perforated door 22 then securely fastened with appropriate bolts or clamps over the opening. The charge is now heated to the approximate melting point of the lower melting component, with exhaust fan 27 in operation to remove the products of combustion as well as the water, oil, and grease vapors which are almost invariably present in the materials in question. The rotating mechanism is now set in motion and a suitable receptacle is placed under the cylinder to receive and hold the molten portions of the charge as they flow through perforations of door 22 whenever same is in downward position. It is now that the fins 30 perform their function by collecting and leading the molten globules of metals toward the door 22 and preventing the same from traveling towards the ends of the cylinder and mixing again with the solid parts of the charge. During the rotation of the cylinder 10, the charge is continually turned over and over so that absolute uniformity of temperature is obtained in every part of the charge. This new apparatus therefore affords a distinct advantage over many types of existing furnaces since such uniformity of temperature is practically never attained in their use. Furthermore, the molten globules of metal always gravitate to the lowest point of the cylinder and, guided by the fins towards the perforated door, are readily and constantly removed.

The fins also perform another important func-

tion, namely, they lift and turn over the solid particles of the material and thereby loosen and free any adhering molten particles, which are then guided to the perforated door. As was mentioned above, the perforated door is interchangeable, thus allowing for variation in the size of perforations to conform to the material treated. Obviously, the smaller the higher melting particles are, the smaller are the perforations, and vice-versa. It is also mentioned that the completion of the separation is readily observable. When no more of the molten globules of metals issue through the perforated door, the operation is finished.

15 I claim:

1. Apparatus of the class described comprising: a rotatably supported cylindrical furnace provided with hollow trunnions for introducing gaseous fuel and for exhausting the products of combustion and the values contained therein, an opening in the center of the cylindrical wall for charging the furnace, a door for closing the opening and provided with means to permit the discharge, as they liquefy, of the lower melting point metallic values, and a plurality of fins attached to the inside of the cylindrical furnace wall, following the curvature thereof from each end toward the door.

2. Apparatus of the class described comprising: a rotatably supported cylindrical furnace comprising, an insulated metallic shell provided with hollow trunnions for introducing gaseous fuel and for exhausting the products of combustion and the values contained therein, an opening in the center of the cylindrical wall for charging the furnace, a perforated door for covering the opening to permit the discharge, as they liquefy, of the lower melting point values, and a plurality of fins attached to the inside of the cylindrical furnace wall, following the curvature thereof from each end toward the door.

3. Apparatus of the class described comprising: a rotary furnace having means for charging the furnace with objects for the removal of metals therefrom as they liquefy and are vaporized and provided with a withdrawal zone in the center of the wall thereof; and a plurality of fins for guiding the lower melting point values to the withdrawal zone.

50
